AUTOMOBILE

Joseph J. Mascuch, Maplewood, N. J.

Application May 5, 1955, Serial No. 35,842

Term of patent 14 years

(Cl. D14—3)

Figure 1 is a side elevational view of an automobile, showing my new design with the side opposite being similar to the one illustrated;

I claim:

The ornamental design for an automobile, substantially as shown.
